UNITED STATES PATENT OFFICE

2,474,435

VACUUM TUBE AMPLIFIER

Robert C. Moore, Philadelphia, Pa., assignor, by
mesne assignments, to Philco Corporation,
Philadelphia, Pa., a corporation of Pennsylvania

Application January 8, 1945, Serial No. 571,935

5 Claims. (Cl. 179—171)

1

This invention relates to an electrical apparatus and particularly to an amplifier having large voltage output. This invention in particular relates to an amplifier having a wide frequency response as in video work where substantial voltage swings are desired.

As is well known, the extended response of a video amplifier precludes the use of transformers for boosting voltage swings. In fact, video amplifiers as a practical necessity are restricted to the impedance-capacity coupled type. In order to obtain large voltage variations in such an amplifier, it is necessary to have substantial current in a moderate-size resistor.

In order to provide high voltage output, it has been necessary to employ tubes having substantial power handling ability. Apart from the expense of such tubes, the large size of the tubes and associated equipment results in high distributed capacitance and tends to reduce the high frequency response.

This invention provides a means whereby video amplification and substantial voltage variations are obtained with conventional equipment. While distributed input capacitance of apparatus utilizing the invention is comparable with that of a simple video amplifier, the invention provides means for obtaining increased amplification. The invention has many advantages in addition to the elimination of high power equipment. Thus, the output capacitance of a group of vacuum tubes is greatly reduced due to the disposition of the tubes.

The invention in general contemplates the disposition of a number of tubes in series one above the other with regard to potential. The input signal is applied to the bottom tube in the series. Each tube transmits the amplified signal to the tube above it, the connections being so arranged that the gain in each tube is added to that of the tube below it. More specifically, the anode of a lower tube is conductively connected to the cathode of the next higher tube, while the grid of the higher tube is connected from a point on the load resistor of the lower tube. By virtue of this arrangement, proper phase reversal is obtained, so that the gain is cumulative. This is to be distinguished from a simple superposition of tubes wherein the gain of all the tubes is no greater than the gain of any one.

In order that a more detailed description of the invention may be given, reference will now be made to the drawings wherein Figure 1 is a circuit diagram of one form of the invention. Fig-

2

ure 2 is a circuit diagram of a modified form utilizing a common power supply.

Referring first to Figure 1, the lowermost vacuum tube 10 has cathode 14 grounded at 12. Tube 10 has control grid 13 connected through grid resistance 14 to bias source 15 and thence to ground. It will be noted that bias source 15 has its negative terminal connected to the grid while the positive terminal is grounded. An input circuit to control grid 13 may be provided through blocking condenser 17, the other terminal of the input being at ground.

Vacuum tube 10 has anode 20 connected through load resistance 21 to the positive terminal of plate voltage source 22 whose negative terminal may be grounded. It is understood that plate voltage source 22 and bias source 15 have suitable voltage ranges for energizing vacuum tube 10.

From anode 20 of vacuum tube 10, lead 25 goes to cathode 26 of vacuum tube 27, this being the next one above tube 10. Cathode 26 is connected through bias source 28 and grid resistance 29 to control grid 30. An input circuit to control grid 30 is provided through blocking condenser 31 by lead 32 connected to point 33 on load resistor 21. Vacuum tube 27 has anode 35 connected through load resistance 36 to plate voltage source 37 and thence back to cathode 26.

Anode 35 is connected by lead 40 to cathode 41 of the next higher tube 42. Cathode 41 is connected through bias source 43 and grid resistance 44 to its control grid 45. An input circuit to control grid 45 is provided through blocking condenser 46 and lead 47 taken from point 48 on load resistance 36. Vacuum tube 42 has anode 50 connected through load resistance 51 and plate voltage source 52 to cathode 41.

The output of the system may be taken between anode 50 and ground. Tubes 10, 27, and 42 need not necessarily be of the same type. However, since all the tubes handle the same order of space current, it is preferably that the tubes be similar. Points 33 and 48 on the load resistors are preferably so chosen as to impress the proper portion of the voltage swing due to each tube to the grid of the tube above it. In practice, the voltage variations between point 33 and anode 20 should be approximately equal to the voltage swing due to signals at control grid 13. The same is true of the voltage swing between point 48 and anode 35. The magnitude of load resistors 21, 36, and 51 will all be determined by usual design methods.

For purposes of explanation, a one-volt signal

each tube and circuit will be assumed. If grid 13 goes towards positive by one volt, anode 20 will go negative by ten volts. This means that cathode 26 will go negative by ten volts. On the other hand, point 33 will only go negative nine volts, so that grid 30 will go positive by one volt with respect to its cathode. Thus, cathode 26 will be minus ten volts and grid 30 will be minus nine volts. This will result in anode 35 being at minus twenty volts. Point 48 will be 10 at minus nineteen volts. Thus, grid 45 and cathode 41 will be respectively at minus nineteen volts and minus twenty volts, so that anode 50 will be at minus thirty volts.

It is understood that, in this analysis, only 15 alternating potentials are considered. It is clear that the gain of the entire system is the gain of all the tubes added together. If the tubes are all alike and the gain is the same, then the total gain will be the gain for one tube times the number 20 of tubes.

The input capacitance, as seen from blocking condenser 17, will be the input capacitance of a single tube. The output capacitance of the system of Fig. 1 consists of the output capacitances of the tubes 11, 27 and 42, each of which is across its respective resistor 21, 36 and 51. The total output capacitance is thus reduced by the series relation.

The system described above suffers from the requirement of a plurality of power supplies. Due to the physical size of such power supplies, the distributed capacitance may be objectionably high, in addition to the inconvenience and expense of separate power supplies. In order to eliminate this, the system shown in Figure 2 is provided.

In this system, the input circuit goes to blocking condenser 60 thence to control grid 61 of the lowest tube 62. Tube 62 has cathode 63 connected to ground through bias resistance 64. Control grid 61 is connected to ground through resistance 65. Tube 62 has anode 66 connected through condenser 67 to junction point 68. Junction point 68 has connected thereto resistances 69 and 70 in series. Resistance 70 is connected to source 70' of B+ potential. This B potential source should have a sufficiently high value, so that the tubes in series may be properly energized. Thus, assuming that three tubes are used as shown here and that the tubes are similar and operated similarly, then the B supply should have a voltage at least three times that necessary to operate one tube, but the current requirements of the source are moderate.

From point 71, which is the junction between resistors 69 and 70, lead 72 goes to blocking condenser 73 and the latter is connected to control grid 75 of succeeding tube 76. Tube 76 has cathode 77 connected through bias resistance 78 to anode 66. Anode 66 is connected through grid resistance 79 to control grid 75. Vacuum tube 76 has anode 80 connected through blocking condenser 81 to point 82. Point 82 is connected to junction point 68 through resistances 83 and 84 in series. From junction 85 between resistors 83 and 84, lead 86 goes through blocking condenser 87 to control grid 88 of tube 89. Cathode 90 is connected through bias resistance 91 to anode 80, and is connected through grid resistance 92 to control grid 88. Tube 89 has anode 93 connected by lead 94 to resistance 95 and then to junction point 82.

The output of the entire system is taken between ground and anode lead 94 while the input is be-

tween ground and blocking condenser 60. The entire series of resistors between anode lead 94 and potential source 70' constitutes a load resistor for the amplifier system. By-pass condenser 96 may be connected between ground (or cathode 63) and resistance 70.

The junction points between load resistors for one tube are so chosen that the signals impressed on the grid of the next tube equal in amplitude the signals on the tube below. Thus resistances 69 and 70 are so chosen that point 71 feeds signals to control grid 75 equal in amplitude, with respect to cathode 77, to the signals impressed upon grid 61. It is thus possible to omit blocking condensers 67 and 81 completely and their connections to the anodes of tubes 62 and 76, when the tubes are all similar and have substantially equal input signals.

Any type vacuum tube may be used that is desired. Thus, it is possible to use tetrodes or pentodes and obtain the benefits of low output capacitance and high voltage output. In the event that pentodes are used, the usual connections between electrodes and the load resistance will be made. Thus, tube 89 has resistance 95 as the load, and any suitable potential sources bypassed to the cathodes may be taken for connection to the additional electrodes of a pentode.

It is understood that the heaters in the various 30 tubes will be suitably energized. The cathodes of the various tubes are all at different potentials. This would mean that the heaters would either have to be at one potential, if a single current source were used, or might have individual filament windings isolated from the remaining filament windings. In certain types of tubes, it is possible to maintain a substantial difference in potential between the heater and cathode so that a common heating source may be used. However, 35 separate heating sources suitably isolated from each other may be preferable, particularly if provision is made for keeping the capacity to ground of the winding or other source at a minimum.

The low frequency response of the system may 40 be made as good as any system having comparable amplification. In fact, the limiting factor for low frequency response is the size of the coupling condenser. In the system shown here, the number 45 of coupling condensers is equal to the number of tubes used. Due to modern improvement in condensers, it is possible to obtain substantial capacitance with small physical size so that, in practice, 50 the high frequency response for the system described here may be carried to about the same 55 place in the frequency spectrum as in a conventional system.

By virtue of the invention herein, an amplifying 60 system is provided having substantial voltage output and desirable characteristics. A video amplifier inherently has a load whose impedance is small in comparison to the impedance of the 65 amplifier tube. In the system herein disclosed, the load resistor for the entire system may be considered as the normal individual tube loads connected in series, each tube driving the tube 70 above it in the series. The output of the system provides a source of signal of higher voltage, and at a greater impedance level than is available from a single tube of the type selected, while the frequency characteristics approximate those of a well designed amplifying stage using a single tube 75 of the type selected.

What is claimed is:

1. An amplifying system comprising a plurality 75 of vacuum tubes, each vacuum tube having a

cathode, control grid and anode, means connecting said tubes in series so that the anode of each tube in the series is connected to the cathode of the following tube in the series, an input circuit connected to the control grid of the first tube in said series, a load resistor system connected to the anode of the last tube in the series, a source of energizing potential connected between the cathode of the first tube in the series and the load resistor system, bias means for said grids, connections from said load resistor system to the control grids of the tubes above the first tube in the series, said connections being so chosen that the amplitude of signals impressed upon all control grids is substantially the same, said system also having a condenser connected between a point on the load resistor system on the one hand and between the anode of one tube and the cathode of the next tube in the series on the other hand, each tube beyond the first in the series having such a condenser and wherein the point of connection on the load resistor system is so selected as to divide said load resistor system into separate load resistors for each tube.

2. In an amplifying system, a plurality of vacuum tubes, each tube having cathode, control grid and anode, means for connecting said tubes in series with the anode of each tube in the series connected to the cathode of the next tube in the series, a bias resistance between the anode of one tube and the cathode of the next tube in the series, an input circuit to the control grid of said first tube in the series, a load having one terminal connected to the anode of the last tube in the series, a source of potential connected between the other terminal of the load and the cathode of the first tube in the series, connections from said load to the control grids of the tubes above the first tube in the series, each such connection including a blocking condenser and being made to a point on the load where the amplitude of voltage variation is such as to provide signals on the control grids substantially equal in amplitude to the signals on the grid of the first tube, and an output circuit across said load.

3. The system of claim 2 wherein a condenser is connected between each cathode and a point on the load whose potential variation is substantially the same as that of the cathode.

4. An amplifying system comprising a plurality of vacuum tubes, each vacuum tube having a cathode, control grid and anode, means connecting said tubes in series so that the anode of each tube in the series is connected to the cathode of the following in the series, an input circuit con-

nected to the control grid of the first tube in said series, a load resistor connected to the anode of the last tube in the series, a condenser connected between a point on the load resistor on the one hand and between the anode of one tube and the cathode of the next tube in the series on the other hand, each tube beyond the first in the series having such a condenser, the point of connection on the load resistor being so chosen as to divide said load resistor into separate load resistances for each tube, a source of energizing potential connected between the cathode of the first tube in the series and the load resistor, bias means for said grids, and connections from said load resistor to the control grids of the tubes above the first tube in the series, said connections being so chosen as to feed signals of desired amplitude and phase to said control grids.

5. In an amplifying system, a plurality of 20 vacuum tubes, each tube having cathode, control grid and anode, means for connecting said tubes in series with the anode of each tube in the series connected to the cathode of the next tube in the series, an input circuit to the control grid of said first tube in the series, a load connected to the anode of each tube in the cathode-anode circuit thereof, means for impressing input signals on the control grids of tubes above the first in the series from points on the load, the input for any tube 30 being derived from the load of the preceding tube in the series with the points on said load being so chosen as to provide input signals of equal amplitudes for all the tubes, means for biasing said grids relative to said cathodes, means for impressing suitable energizing potentials on the anodes of said tubes and an output circuit connected between the cathode of said first tube in the series and a point on the load of the last tube in the series, said vacuum tubes being similar and 40 operated similarly.
